UNITED STATES PATENT OFFICE.

CHARLES WHITTIER, OF BOSTON, MASSACHUSETTS.

GUARD FOR ELEVATOR-SHAFTS.

SPECIFICATION forming part of Letters Patent No. 308,936, dated December 9, 1884.

Application filed July 21, 1884. (No model.)

To all whom it may concern:

Be it known that I, CHARLES WHITTIER, of Boston, county of Suffolk, State of Massachusetts, have invented an Improvement in 5 Safe-Guards for Elevator-Shafts, of which the following description, in connection with the accompanying drawings, is a specification, like letters on the drawings representing like parts.

10 This invention has for its object to provide a barrier or guard for elevator-shafts to close or bar the several openings or doorways which lead from each landing or floor of a building into the elevator-shaft or the car therein as it 15 travels up and down in said shaft, all of the several openings or doorways being closed by the safety apparatus whenever the car is between any two floors, while, when the car reaches a floor or landing having a doorway 20 opening into the shaft, such doorway alone is freed from the barrier to permit passage to or from the car and landing.

The nature of my invention consists, primarily, of an elevator-car having suitable 25 means to raise or lower it in an elevator-shaft, a group of pulleys or sheaves supported in the upper part of the elevator-shaft, and a second group of pulleys or sheaves arranged in the lower portion of said elevator-shaft, combined 30 with a gang or series of ropes having their ends secured, respectively, to the top and to the bottom of said car, the said ropes passing over and under the sheaves in the upper and lower portions of the elevator-shaft, the said 35 sheaves being arranged in V form, the pulleys for each rope above and below the car being in different horizontal planes, substantially as hereinafter fully described, and particularly pointed out in the claims.

40 Figure 1 shows in vertical section a portion of an elevator-shaft, with the car in elevation and with my invention properly applied; Fig. 2, a transverse section of the shaft-walls and car, to clearly show the shaft and the arrangement of the car and the guide-ropes therein.

45 In the drawings, A represents an elevator-car of any suitable construction, and adapted to be moved up and down in the elevator-shaft B by any preferred known mechanism 50 used for that purpose. The car is provided

with the usual doorway, a, which may be closed by the door b. The adjacent or like ends of a gang or series of ropes, e, are fastened to the top or upper part of the car above the doorway a, and, extending upward, pass about a 55 group of pulleys or sheaves, c, supported on the hanger or angular plate C, which is secured in the upper part of the shaft, the ropes then extending down past and in front of the car and to one side of the doorway a thereof 60 to the bottom or lower part of the shaft, where they pass about a second group of pulleys, d, supported in the bracket or angular plate D, secured in the bottom of the shaft, after which the ropes are secured at their lower ends to 65 the bottom of the car, beneath said doorway a, all as clearly indicated in Fig. 1.

As herein shown, the groups of sheaves are arranged on brackets or angular plates, so that all the ropes except one pass about two pulleys in each group, in order to properly span them, as will be readily understood. Commencing with the center rope, which is the shortest, each rope of the series in succession is longer than the rope arranged inside of it 70 toward the center rope, each rope in succession passing over pulleys in different horizontal planes. The gang or series of ropes is arranged in the same vertical plane at the front of the elevator-shaft or next one of its four 75 walls only. As the car is moved upward toward a doorway, G, on a floor or landing, the guard or barrier of ropes above the top of the car bars such doorway, passing upward over the pulleys c; but the ropes, rising in unison 80 with the car, uncover the doorway by the time that the car reaches the landing or the platform of the car arrives substantially at the level of the doorway, the shaft or landing permitting free passage to be made from or to the 85 car and landing. Thus it will be seen that all the doorways leading to the well or elevator shaft are constantly barred, except when the car reaches a landing, when the doorway at such landing is free from any barrier or guard 90 whatever.

By arranging the gang of ropes at the front of the shaft only I am enabled to economize very considerably in the amount of rope required, as well as in the number of pulleys 95 100

demanded, and the flexible barrier in no way interferes with the operating mechanism for or the guides of the car.

Instead of ordinary hemp rope, I may use 5 bands or the more flexible of wire ropes that may be suitable for the purpose desired.

In Fig. 2 a doorway, C, on a landing or floor is shown, which, when the car is above or below it, is barred by the gang or series of ropes, 10 as stated.

The car herein shown will preferably be moved as in my United States Patent No. 154,108, to which reference may be had.

I claim—

- 15 1. An elevator-car placed in an elevator-shaft, and a group of pulleys in the upper part of the shaft and a group of pulleys in the lower part of the said shaft, each group of pulleys being arranged in V form, combined with a 20 gang or series of ropes having their ends secured, one at the top and the other to the bottom of the car, the said ropes running about the groups of pulleys, the pulleys for each

rope of the series, both above and below the car, being arranged in different horizontal 25 planes, substantially as set forth.

2. An elevator-car placed in an elevator-shaft, and two groups of pulleys, arranged one above and the other below the car, and secured to or near one wall of the elevator-shaft, 30 combined with a gang of ropes connected at one end to the top of the car at the front thereof, and at their other ends to the bottom of said car at the front thereof, each of said ropes between the pulleys supporting it crossing 35 vertically the face of the car, the independent ropes from the center to the outside rope of the series varying in length, to operate all substantially as described.

In testimony whereof I have signed my 40 name to this specification in the presence of two subscribing witnesses.

CHARLES WHITTIER.
